(57) CLAIM

The ornamental design for a shower enclosure, as shown and described.

DESCRIPTION

FIG. 1 is a front/left side perspective view of a shower enclosure showing our new design;

FIG. 2 is a front elevational view thereof;

FIG. 3 is a cross-sectional view taken along line 3-3 of FIG. 2 thereof;

FIG. 4 is a cross-section view taken along line 4-4 of FIG. 2 thereof; and,

FIG. 5 is a top plan view thereof.

The broken lines are for illustrative purposes only and form no part of the claimed design.
